CLAIM

The ornamental design for an ice mold wedge, as shown and described.

DESCRIPTION

FIG. 1 is a front-facing perspective view of an ice mold wedge according to the present design.

FIG. 2 is a rear-facing perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in FIG. 8 show an aperture or portion thereof and form no part of the claimed design.
